UNITED STATES PATENT OFFICE.

RICHARD G. WOOD, OF CINCINNATI, OHIO, ASSIGNOR TO PATRICK REILLY
AND JAMES E. REILLY, OF NEWARK, NEW JERSEY.

DASH-MAKING MACHINE.

SPECIFICATION forming part of Letters Patent No. 329,424, dated October 27, 1885.

Application filed August 14, 1885. Serial No. 174,394. (No model.)

To all whom it may concern:

Be it known that I, RICHARD G. WOOD, a citizen of the United States, residing in Cincinnati, Hamilton county, Ohio, have invented 5 certain new and useful Improvements in Automatic Leather-Stretchers and Dash-Sacking Mechanisms, fully described and represented in the following specification and the accompanying drawings, forming a part of the same.

The object of this invention is to stretch leather by grasping its opposite edges in any manufacturing process, for which purpose the leather may be clamped while the leather is either wet or dry, and the particular application 15 of the machine to stretching dash-leathers and fitting the frames thereto, as illustrated herein to show the operation of the machine.

This invention consists in the combination, 20 with a suitable frame, of two pairs of jaws adapted to grasp the leather and stretch it longitudinally, and of two racks fitted in slides parallel with the jaws and adapted to force the dash-frame into the leather while stretched.

It also consists in several details of construction specifically claimed.

Figure 1 represents the top of the machine, showing the dogs pushed inward to their full- 30 extent. Fig. 2 is an edge view of the same with the jaws opened; and Fig. 3 is an end view of the same with the racks extended to admit the dash-frame, the frame being in section on line *x x* in Fig. 1. Figs. 4 and 5 are 35 respectively top and bottom views of the machine upon a smaller scale, Fig. 4 showing the application of a dash-frame between two sheets of leather clamped in the jaws, while Fig. 5 represents the bottom of the machine, 40 to show the fitting of the screws to the jaws.

The frame of the machine is shown with four parallel bars, *A A'*, across which the jaw-beds *B* are fastened, with lugs *B'* projecting inside the bars *A* and bolted to seats *C* upon 45 guides *C*, which are applied to the opposite side of the frame to carry the racks *D*. Upon the lower side of each jaw-bed is mounted a nut, *e*, and right and left hand screws *f* and *g* are fitted, respectively, to such nuts and 50 united at the middle of their length, so as to

move the jaws longitudinally on the frame when the screw is turned by the hand-wheels *H* at the ends thereof. A movable jaw, *I*, is hinged to the rear edge of each jaw-bed at *I'*, and is pressed toward the bed by an eccentric, 55 *J*, pivoted at its ends *a* in posts *k*, which are projected from the jaw-beds through openings *l* in the jaws. The jaw-beds and jaws are of sufficient length to grasp the edge of the leather which is to be stretched, the latter being laid 60 upon the jaw-bed and the edge of the jaw *I* pressed toward it by turning the cam with the handle *N*. To prevent the springing of the jaw and an imperfect grasp upon the leather at any point in its length, the eccentric is 65 made as a roller nearly as long as the jaw, with eccentric pivots *a* at each end, and the rigidity and extended bearing of such roller upon the back of the jaw suffices to hold the same firmly on the leather through its en- 70 tire length. Straps *m* hold the jaws *I* in contact with the eccentrics, and the latter are rotated at pleasure by handles *N*, inserted in holes in eccentrics.

Fig. 4 shows a double sheet of leather, *L*, 75 clamped by its opposite edges in the jaws, and stretched by separating the same through the agency of the screws *f g*.

P is the dash-frame, which is to be inserted between the two sheets of leather while 80 stretched, and *o* are dogs adapted to press against the outer end of the dash-frame and force it into the stretched leather, where it may be secured while the leather is under tension by rows of stitches *r*, formed in the leather 85 close to the edges of the dash-frame.

In Fig. 3 the guides *C* are clearly shown, as well as their mode of attachment to the jaw-beds, although upon the opposite side of the frame from the latter, and the racks *D* are 90 shown provided with teeth *D'*, into which is fitted a pinion, *S*, mounted upon a spindle, *s*, provided with a hand-wheel, *T*, and hung in bearings at the outer end of the guide *C*. The dogs *o* are slender bars clamped in sockets 95 *q* upon the racks *D*, their ends being notched to bear against the dash-frame, so that the inward movement of the racks will push the dash-frame firmly into the stretched leather. The dogs shown in Fig. 4 are shown provided with

a lateral prong at the inner side, adapted to engage with such iron frames as are very narrow, like those of wheel-guards, and the dogs may be made of any other shape that is found necessary. The racks are shown in Fig. 2 fitted to the guides C by opposite tongues d; but the means for fitting the racks to the guides is immaterial, as the essential feature of the invention is the combination, with the two movable jaws and their right and left hand screws, of the racks sustained upon the same frame and operating parallel with the jaws to press the iron frame into the leather while under tension.

15 Having thus described my invention, what I claim herein is—

1. In a leather-stretching machine, the clamping mechanism consisting in the jaw-bed B, the jaw I, hinged thereto at one edge as described, the openings l through the jaws, the posts k, attached to the bed and projected through the openings, and the eccentric J,

bearing upon the back of the jaws, the eccentric being fitted longitudinally along the back of the jaw, so as to press its edge toward the bed through its entire length, substantially as shown and described.

2. The combination, with the frame formed of parallel bars A A', of the jaw-beds B, the jaws I, and eccentrics J, mounted movably upon one side of the frame, and the guides C, secured thereto upon the opposite side of the frame, the nuts e, and screws f g, applied to the frame and jaws, and the racks D and pinions S, mounted upon spindles s, substantially as herein shown and described.

In testimony whereof I have hereunto set my hand in the presence of two subscribing witnesses.

RICHARD G. WOOD.
